DENTAL FLASK

Charles S. Ballard, Seattle, Wash.

Application March 25, 1933. Serial No. 662,789

6 Claims. (Cl. 18—33)

My present invention relates to the art of dental mechanics and more particularly to a dental flask.

Dental mechanical work often requires a flask capable of positively securing certain dental parts, under pressure, while they are encased in a plaster matrix or mold and permit their being subjected to dry heat as in drying and the later continuous curing of the same at a specific temperature for a considerable period. It is to provide a convenient method and the necessary mechanical equipment to facilitate this molding and curing that I have provided my flask.

The conditions under which such materials are molded and treated requires a flask of rather substantial construction so that considerable pressure can be applied to the dental part. After the plaster or other suitable matrix has set it is then desirable to subject it to a sequence of heat treatments. With my flask I provide an interlining so arranged that the plaster can be cast in the interlining and the whole surrounded by my flask proper which is built with the required strength for this operation. Then in order to save unnecessary capital investment the interliners can be removed with the set plaster and the flask housing be used again with other liners during the period that the first interliners and their contained plaster casts are subjected to the necessarily prolonged treatment.

During the heat treatment it is highly essential that accurate temperatures be maintained and this presupposes an accurate temperature indicating arrangement. With my flask I provide that when the plaster cast is prepared, that a suitable recess be provided in the plaster and that the same be provided with a metal bushing which will be properly placed so that during the curing process a suitable thermometer may be placed in position in such a manner that the temperature can be constantly observed yet the thermometer itself will not be affected by the metal of any part of my flask.

Other and more specific objects will be apparent from the following description taken in connection with the accompanying drawings, wherein.

Figure 1 indicates a top view of my flask complete, certain parts being broken away to more clearly disclose the structure employed.

Figure 2 is a side elevation of Figure 1, part of which is shown in section as though taken along line 2—2 of Figure 1.

Figure 3 is a cross sectional view thru my flask complete the same being shown in elevation

and with a thermometer, of the type used, in position.

Figure 4 illustrates in fragmentary sectional view the recess forming plug as it is in position when the plaster is poured into the flask. 66

Figure 5, represents, in an exploded view arrangement, some of the various parts making up my complete flask.

Figure 6, is a perspective view showing a modified form of my interlining. 65

Figure 7 is a perspective view showing one of the centering plugs used to center the upper and lower member of my flask and also to secure the same in position.

Figure 8 indicates in perspective the recess forming plug and the thermometer bushing. 70

Figure 9 indicates in perspective exploded arrangement the various parts forming my spring locking means.

Referring to the drawings, throughout which like reference characters indicate like parts, numerals 10 and 12 designate respectively the upper and the lower portion of my dental mold or flask. These parts are normally formed of cast material that is not readily affected, chemically, by the materials used and will withstand heat and pressure. I have found brass to be very satisfactory but any suitable non-ferrous metal could be used. Lower member 12 is provided with a solid bottom 14 made integral with the drag portion of the flask. The upper, or what corresponds to the cope portion, 10, is provided with a removable cover 16 which may be secured to member 10 in any manner which will form a secure engagement therewith. In the drawings, 75

herewith, I have indicated one arrangement as having cap or set screws 18 threaded therein and arranged to engage in a suitable recess 20 formed in the centering pin or post 22. It has been found desirable however to have post 22 fixedly secured 80 in member 10 as by threads shown at 24. The lower portion of pin 22 should preferably have a cylindrical portion 26 and then a tapering end portion 28 so that it may first be easily engaged in bore 30 of member 12 and then as it progresses 85 downwardly the cylindrical portion 26 will provide accurate alignment of the two halves 10 and 12. 90

It is highly desirable to have a method of snapping the two portions 10 and 12 together 105 automatically, to the end that unnecessary time of an attendant will not be consumed in the operations of molding and pressing. This is provided by a latch member 32 suitably guided within boss 34 formed as part of member 12 and hav- 110

ing the same arranged with a coil spring, preferably, as 36 which constantly urges latch 32 into engagement with a recess 38 in pin 22. As a further convenience, latch 32 is provided with a 5 normally downwardly extending handle portion 38 which in addition to serving as a handle for the retraction of latch 32, which could be grasped and pulled directly outwardly may also act as a cam follower. I find it desirable to employ an 10 inserted annular cam member 40, arranged in such a manner that as handle 38 is revolved upwardly it engages cam 40 to withdraw latch 32 from recess 38 and when it is fully withdrawn it is adapted to rest in the locking notch or slot 15 42 formed in the surface of cam 40.

Cover plate 16 is provided with a plurality of holes 44 which serve as a convenient escape means for surplus plaster.

Adapted to seat within the flask are the two 20 companion flask interlining members 46 and 48. These are of such a size that they will easily go into the interior of the flask and be spaced somewhat from it except on the medial plane where outstanding lips which are of necessity provided 25 for resting and spacing the flask members. Thus the interliners 46 and 48 are adapted to engage members 10 and 12 respectively and be centered and spaced therefrom by the outstanding lip or ledges 50, 51, 52 and 53 respectively. These ledges 30 are cut away as at 55 and 57 so as to engage the upstanding rim lugs 60 and 62 of members 12 and 10. This arrangement provides for the accurate centering and positioning of the interliner as a whole.

35 The two portions of the interliner are also provided with male and female centering and securing means as the male portions 64 and the female guide 66 which they engage respectively.

Each of the interliner members 46 and 48 are 40 provided with corresponding half grooves 68 which when the two halves are placed together in operating relationship forms excess plaster discharge openings as 70 freely communicating with the outside of the flask proper. In order 45 to further increase the retaining ability of the interliners for the molded material cast therein each of the interliner members are provided with an inwardly extending ledge as 72 and 74.

In Figure 5, I have shown a still further modification which might be taken as a fair representation of either the upper or lower interliner member which has all the features enumerated and in addition is slit, preferably, along its minor axis so that molds can be more easily removed 50 under certain conditions and further they are provided with inwardly extending fin members as 76 which are so arranged that the molds can be loosened and pulled off the cast material. Interlocking securing means should be provided to secure the two halves together as indicated at 77.

The curing of the denture material requires 65 prolonged heating with a dry heat, at carefully regulated temperatures. To insure this uniformity it is necessary to use a thermometer so arranged as to give accurate readings. With this in mind I have provided in one of my flask members an opening as 78 which is adapted to receive a cavity forming plug. This plug is 70 shown most clearly in Figures 4 and 8 as 80 and is provided with a handle portion 81, a reduced size portion 83 which is adapted to form a snug fit in the outer flask member and then a reduced portion 84 of such a size as to hold, in proper position, the closed end thimble 86. When the 75 plug is removed, which will normally be as soon

as the cast has set, the thimble is left inside so as to provide an accurate and uniform heat transmitting receiver for the thermometer 88. It is desired to call special attention to the relieving of the outer flask and the interlining flask member as shown at 78 and 90 so that the thermometer will not touch any metal excepting the thimble 86. The plug should further be of such a size as to provide that the cast material itself does not touch the thermometer after the showing of Figure 3. Handle portions 91 and 92 are normally formed as part of the interliner members to assist in the easy handling of the same.

As an alternate arrangement I have shown a modified securing means for a top plate 16. This consists of a bolt arrangement employing a thru bolt 93 to which is secured an operating handle 94 which is arranged to provide operating means for sliding bolt 93 into engagement with post 22 and out of engagement therewith the same being held in the engaged and freed position by a lug 95 arranged to provide two handle receiving notches as 96 and 97.

Method of operation

To more clearly explain the operation of my flask to the end that the particular purposes of the various features may be more clearly understood let it be assumed that my flask is being used in producing a false tooth plate assembly.

Now normally an impression is made in wax of the oral cavity which is to be fitted with a plate, by filling the flesh engaging portion of the impressions thus obtained with a hard setting plaster the foundation stone 98 is obtained. 105 This is normally formed with a flat bottom surface as an added convenience in handling such as is shown in Figure 3. Now the upper surface of this stone carries the form of the oral cavity the plate is intended to fit. The next operation 110 normally is to secure in place on the stone 98, by means of low melting wax, the various teeth in their proper arrangement. These are indicated at 99 in Figure 3. The next operation is to place the stone with the teeth secured thereto into 115 the lower flask member 12 with its interliner 48 and which has been previously filled with a semi-fluid plaster. The stone is imbedded in the same to such an extent that the wax retaining the teeth remain practically on the parting line. The 120 upper half of the mold is then put in place with its interliner 46 and the entire mold is filled full of fluid plaster of Paris, by this is meant plaster of Paris which has been mixed with sufficient water to wet all the powder particles. Cover 16 125 is then placed in position as is also the cavity producing plug 80, shown in its proper position in Figure 4, placing the cover on the mold and pressing the same into position assures that the entire mold is filled, the excess being forced up 130 and out the various openings provided, such as 44 and 70. Before the plaster in the lower half is poured and before the upper half is poured upon the lower half some parting medium should be placed on the lower surface to the end that 135 the plaster cast can be parted at the center of the mold and also easily removed from the lower half.

Before pouring the upper half in position it is 140 customary to normally provide waste grooves or draining channels, in the slightly hardened lower half, which extend outwardly to opening 70. As soon as the plaster has set the cast is placed in hot water and the wax softened so that it will either drain away from the teeth 99 or can be 145

easily washed away with hot water when the mold is parted.

The cast with the two interliners surrounding it can now be removed from the flask and placed over any source of dry heat to thoroughly dry the cast material. This makes it possible to use one mold proper formed of members 10, 12 and 16 with several sets of interliners thus affecting a considerable saving due to the fact that the more expensive flask is not tied up during the drying process.

After the mold is dried thoroughly and the plaster set firmly the teeth 99 will be held securely in the upper flask and stone 98 will be secured within the lower portion of the flask. The plate blank is then placed between stone 98 and the teeth 99. The flask is reassembled and the whole device placed in a heating press. Naturally as the un-cured blank is considerably too large for the cavity formed previously the two halves of the flask will not meet but as pressure and heat is applied the two halves will gradually force the surplus material out of the central space in the mold thru the discharge openings 70 and as soon as the flask has been pressed sufficiently close together bolts 32 will, under urging of their springs 36, engage their recesses 38 within pin 22 thus informing the operator that the pressing is complete and automatically locking the flask to retain full pressure on the mold. The flask may then be removed from the press and the curing continued with any suitable application of heat.

During the curing operation and while the flask is under the heat press it is necessary that thermometer 88 be installed within the sleeve or thimble 86 after the showing of Figure 3 and the heat supplied during the curing process must be regulated to maintain a temperature found most satisfactory for the type of material used in the plate blank. In order that accurate reading can be obtained from thermometer 88 it is desirable that the thimble be well within the cavity substantially as indicated in Figure 3 and in the open end of the U formed by the teeth 99. It is then desirable that sufficient clearance be provided for the thermometer so that it will not touch the cast material, the interliner or the outer member 10 as if it did it would unnecessarily influence the thermometer and inaccurate readings would result.

During the curing process the dead air space between the outer flask members 10 and 12 and the interliners 46 and 48 provides a heat insulating means which tends to equally distribute the heat and prevent local burning of the denture material.

The foregoing description and the accompanying drawings are believed to clearly disclose a preferred embodiment of my invention, as used in dental work, but it will be understood that this disclosure is merely illustrative, that the flask may be used in many fields of industry and that such changes in the invention may be made as

are fairly within the scope and spirit of the following claims:

Having thus fully described my invention, what I claim as new and desire to secure by Letters Patent is:—

1. In a mold the combination with a drag section and a cope section, and clamping means therefor, of a separable inner mold comprising a drag section and a cope section, means for spacing these inner sections within the mold, and means for retaining the inner mold within the outer mold.

2. In a mold the combination with a drag section, a cope section, and a removable cover for the cope section, of a centering pin rigid with the cope section, a fastening device mounted in the cover for engagement with said pin, a socket member on the drag section for receiving said pin, and a detachable fastening device mounted in the socket member for engagement with said pin.

3. In a dental mold the combination with a drag section, a cope section and a removable cover having a socket member rigid therewith, of a centering pin threaded in a part of the cope section, a portion of said pin extending in said socket member and a set screw in said member for engagement with the pin, a socket member on the drag section, and a spring-pressed latch-bolt mounted in the second socket member for engagement with said pin.

4. In a dental mold the combination with a drag section, a cope section, and a removable cover having an exterior socket member, of socket member on the drag section and cope section adapted for alinement with the first socket member, a centering pin having an intermediate threaded portion engaging the socket member of the cope section, a set screw mounted in the socket member of the cover for engaging said pin, an angular spring-pressed, rotatable and slidale bolt mounted in the socket member of the drag section for engagement with the pin, and a cam device for co-action with said bolt in withdrawing the bolt from the pin.

5. In a dental mold the combination with a drag section, a cope section, a removable cover, and clamping means for said members, of a removable recess-forming plug adapted to be inserted through a lateral opening in the cope section, and a separable ferrule on the inner end of said plug, whereby said plug may be withdrawn leaving the ferrule fixed in the wax core.

6. In a mold the combination with a drag section and a cope section, and clamping means therefor, of a separable inner mold comprising a drag section and a cope section, means for spacing these inner sections within the mold, means for retaining the inner mold within the outer mold, a removable recess-forming plug inserted through alined lateral openings in the inner and outer cope sections, and a separable ferrule on the inner end of said plug, whereby said plug may be withdrawn leaving the ferrule fixed in the wax core of the mold.
